US0D1046580S

(12) **United States Design Patent** (10) **Patent No.:** **US D1,046,580 S**
(45) **Date of Patent:** **** Oct. 15, 2024**

(54) **PLIERS**

(71) Applicant: **Milwaukee Electric Tool Corporation**,
Brookfield, WI (US)

(72) Inventors: **Aaron S. Blumenthal**, Shorewood, WI
(US); **Christopher S. Hoppe**,
Cedarburg, WI (US); **Aaron M.**
Williams, Milwaukee, WI (US)

(73) Assignee: **Milwaukee Electric Tool Corporation**,
Brookfield, WI (US)

(**) Term: **15 Years**

(21) Appl. No.: **29/833,551**

(22) Filed: **Apr. 5, 2022**

Related U.S. Application Data

(62) Division of application No. 29/765,030, filed on Jan.
5, 2021, now Pat. No. Des. 951,731, which is a

Deuren s.c.

(57) **CLAIM**

The ornamental design for pliers as shown and described.

DESCRIPTION

FIG. 1 is a perspective view from above of an embodiment
of the claimed design;

FIG. 2 is a perspective view from below of the claimed
design of FIG. 1;

FIG. 3 is a front view of the claimed design of FIG. 1;

FIG. 4 is a rear view of the claimed design of FIG. 1;

FIG. 5 is a left side view of the claimed design of FIG. 1;

FIG. 6 is a right side view of the claimed design of FIG. 1;

FIG. 7 is a top view of the claimed design of FIG. 1; and,

FIG. 8 is a bottom view of the claimed design of FIG. 1.

The broken lines shown are included for the purpose of
illustrating portions of the pliers that form no part of the
claimed design.

1 Claim, 6 Drawing Sheets

Related U.S. Application Data

division of application No. 29/683,160, filed on Mar. 11, 2019, now Pat. No. Des. 910,395.
